KNITTING MACHINE

Thomas S. Hayhurst, Belle Harbor, N. Y., assignor
to Max Nydegger, Summit, N. J.

Application April 13, 1944, Serial No. 530,768

14 Claims. (Cl. 66—63)

The present invention relates to an improvement in knitting machines. Objects of the said invention have been to provide improvements in needle jack conditioning mechanism to effect shaping or gusset forming in knitting machines; and to provide devices for progressively idling needles at edges of the work, either in single or multiple machines, and returning them to active knitting under various conditions to produce extra length at locations where required in the fabric.

One embodiment of my invention in a form adapted for use in connection with an automatic multiple flat links knitting machine is described in the following specification and shown in the drawings appended hereto and in which—

Figure 1 is a view partly in plan and partly in horizontal section of a right end portion of a full automatic links-links knitting machine incorporating the improved needle conditioning mechanism for gusset forming;

Figure 2, a plan view, enlarged, of portions of Figure 1 and with parts removed to disclose details of gusset or shoulder slant forming devices;

Figure 3, a fragmentary view partly in vertical section on the line 3—3 of Figure 2, showing a portion of the devices for effecting rapid return from gusset forming or shoulder slant narrowing;

Figure 4, a fragmentary view in vertical section on the line 4—4 of Figure 3;

Figure 5, an enlarged view in front elevation and with parts broken away of the portion of the machine represented in Figure 1;

Figure 6, an enlarged transverse vertical section on the line 6—6 of Figure 1;

Figure 7, a fragmentary view in vertical section on the line 7—7 of Figure 2 and showing a portion of the gusset or shoulder slant control mechanism;

Figure 8, an enlarged transverse vertical section on the line 8—8 of Figure 1;

Figure 9, a fragmentary view on the line 9—9 of Figure 8;

Figure 10, a fragmentary view showing the relative positions of certain parts while effecting narrowing, as in gusset forming;

Figure 11, a fragmentary view showing the relative positions of said parts during the first step of rapid return or widening in gusset forming;

Figure 12, an enlarged fragmentary view in longitudinal vertical section on the line 12—12 of Figure 8;

Figure 13, an enlarged fragmentary view in

longitudinal vertical section on the line 13—13 of Figure 8;

Figure 14, a fragmentary view on the line 14—14 of Figure 1 showing the control link associated with the automatic widening and narrowing devices employed in gusset forming operations or the like;

Figure 15, an enlarged fragmentary view in transverse vertical section on the line 15—15 of Figure 1;

Figure 16, a view partly in longitudinal vertical section on the line 16—16 of Figure 15 and with portions broken away and with some parts removed;

Figure 17, a horizontal section on enlarged scale on the line 17—17 of Figure 15;

Figure 18, a horizontal section on enlarged scale on the line 18—18 of Figure 15;

Figure 19, a simplified section illustrating the relative positions of the parts shown in Figure 15, for example, when the locking bar is in intermediate or change position and the main jacks are free to be moved upwardly, the selector bar being shown in raised position to engage and lift

25 a profile bar;

Figure 19A, a fragmentary view of parts as shown in Figure 19 and with a lift plate raised to an intermediate main jack lifting position by the selector bar;

30 Figure 19B, a view similar to Figure 19A with the lift plate raised to a higher main jack lifting position;

Figure 20, a simplified section illustrating the relative positions of the parts shown in Figure 19 where the main jack is lifted but the interposed jack has been displaced by the cross jack so that the push jack is conditioned for idling the corresponding needle jack and needle; and

Figure 21, an enlarged fragmentary view in plan of a portion of Figure 1 and with parts broken away to show portions of widening and narrowing control devices employed in fashioning and parts of which are employed in gusset forming or the like.

Gusset forming or shaping

A variation in the control of fashioning devices of the type shown in the appended drawings in part supplements the jacquard and is conveniently employed to produce added fullness in certain portions of the work; and/or to create shaped end edges.

For producing said fullness or shaping, the selected needles are idled alternately at the opposite edges of the work and retain their loops

instead of being idled simultaneously at both lateral edges with decking as in fashioning. Said idling in any given course is effected at that edge of the work toward which the stitch cams are moved in forming that course. After this modified narrowing over the required number of courses, all needles thus idled are restored to knitting condition. The resulting fullness or gusset-like portion, when knitted into the proper part of the back of a sweater, for example, produces in effect a garment with a slanting shoulder section having shape or fullness, thereby conforming more nearly to normal body contours at the nape and shoulder. Other useful applications will be apparent to those skilled in the art of knitting.

For the purposes above stated, parts of devices provided for fashioning, as widening or narrowing with decking, may be actuated and controlled by means operating independently of the actuating and controlling means provided for fashioning. Such fashioning parts, in the illustrated embodiment, include the narrowing cams 311 and 313, the widening cams 312 and 314 and their actuating rods 321 and 322, Figures 15 and 17; the actuating rods 350 and 351 for positioning the lift plates 345 and 346, Figures 15, 16, 18, 19, 19A and 19B, the shafts 360 and 361, and the nuts 356 and 358 mounted on threaded portions thereof respectively, Figure 1. The fashioning shaft 369 is connected to drive said threaded shafts 360 and 361 through sprocket 368 on said shaft 369, chain 367 and sprocket 364 on screw shaft 361, Figure 21. A pinion 365 on shaft 361 drives a pinion 366 on shaft 360. Fashioning shaft 369 and the connected parts may be manually operated by turning handle 369a, or may be mechanically actuated by devices shown in part in Figure 21 and more fully described and claimed in my co-pending application Serial No. 530,766.

In fashioning with said parts, said actuating rods 321, 322, 350 and 351 are advanced and retracted by endwise movement of nut 356 on shaft 360 and nut 358 on shaft 361 which occurs with rotation of said shafts. But in gusset forming, said parts are actuated by endwise movement of said nuts along with endwise movement of said shafts 360 and 361, slidably mounted for that purpose, and the blocks 427 and 426, respectively, Figures 1, 8, 12 and 13, mounted thereon.

As seen in Figure 1, the smooth outer ends of shafts 360 and 361 are slidably supported by bearings in the end wall of housing 359 which forms a bracket 362. Thus, when said shafts are moved endwise in opposite directions for gusset forming, nuts 356 and 358, secured thereon by collars 428, are moved with them and impart equivalent sliding movement to the rods 321, 322 and the cams thereon, and rods 350 and 351 and the lifting plates carried thereby.

Idling of the needles for fashioning and gusset forming in the illustrated machine is effected by operation of the idling cams 311 and 313, Figure 17, which are movable to engage the butts 309 of substantially one half and the butts 310 of the other half of the needle condition controlling cross jacks in each knitting section of a multiple section machine.

Each needle jack 28, Figure 15, may be selectively conditioned: (a) to effect idling of its corresponding needle; (b) to effect links-links operation thereof, or (c) to effect straight knitting, depending on the operative position of its push jack 193. Said position is determined by a set

of control jacks, Figure 15, including a connecting jack 294 engaging said push jack 193, a main jack 293, an interposed jack 295, and a cross jack 291. When interposed jack 295 is positioned between main jack 293 and connecting jack 294, as shown in Figure 19, push jack 193 can be conditioned, i. e. angularly adjusted, by suitable devices operating through main jack 293 to render its needle active. However, with interposed jack 295 withdrawn from between main jack 293 and connecting jack 294, Figure 20, push jack 193 will not be moved inwardly by push-in bar 195. Its needle will, therefore, be or remain idle, regardless of the operation of any other pattern controlling device having the effect of raising main jack 293 to an active position.

Idling or narrowing at one side of the work (left) is effected in any course by moving the narrowing cam 311 to the right, Figure 17, by means of rod 321. Said cam thereby bears successively against depending lugs 309 of one or more cross jacks 291; and moves the latter outwardly (left Figure 15), thus displacing corresponding interposed jacks 295. For narrowing at the right side, Figure 17, rod 322 and narrowing cam 313 thereon are moved endwise to the left, thus moving outwardly the cross jacks 291 having the depending butts 310. When said respective rods are moved in the opposite directions, the restoring or widening cams 312 and 314, respectively engage the depending lug 310 and 309 respectively, to push the corresponding cross jacks 291 inwardly and return interposed jacks 295 to normal operative position, as in Figure 15.

In fashioning, the narrowing and widening changes just described occur simultaneously at opposite sides or edges of the work and involve one or more needles at each side. In the illustrated machine, automatic narrowing by one or two needles at each edge and automatic widening by one needle at each edge in any course, are effected through suitable control devices shown in part in Figure 1. However, in forming gussets or the like, the number of needles idled at one edge of the work in any course may be more widely varied, as up to six needles, for example, in the illustrated machine; and all needles idled at one side in one or more previous courses may be returned to active condition in one course (rapid return).

Narrowing or shaping without decking in gusset forming

Said blocks 426 and 427 through which endwise movement is imparted to rods 321, 322, 350 and 351 in gusset forming are loosely mounted on the smooth end portions of said worm shafts 361 and 360, respectively, on which the nuts 356 and 358 are threaded to permit rotation of said shafts in relation to said blocks for effecting fashioning. Said blocks are held against endwise movement on said shafts between retaining collars 428 secured to said shafts at each end of said blocks.

As seen in Figures 1 and 8, said blocks 426 and 427 are also mounted to slide on and are guided by interior surface portions of the housing 359. In fashioning, these blocks are releasably locked in inoperative condition, as shown in Figure 1, with a right end portion of block 427 overlapping a left end portion of block 426; and the smooth or unthreaded ends of shafts 360 and 361 rotate freely therein.

In gusset forming or shoulder slant narrowing, however, block 426, after release, is moved

to the left, Figure 1, in one course; and block 427, to the right in another course, in predetermined increments depending on the number of needles to be idled in each narrowed course. These movements transmit corresponding narrowing displacement to shafts 360 and 361 and thence to the cams, as 311, 312, etc., and lifting plates 345 and 343, alternately at opposite edges of the work, although said lifting plates here perform no function in relation to decking, since none is required.

The top surfaces of said blocks are provided with sets of transversely extending obliquely disposed teeth to form respectively a ratchet 429 on the inner block 426 and a ratchet 430 on the outer block 427. The outer faces of the teeth of ratchet 429 are exposed obliquely to the left and those of ratchet 430 are exposed obliquely to the right, Figures 12 and 13.

Said blocks 426 and 427 also have sets of downwardly directed teeth forming an inner rack 431 and an outer rack 432, respectively. Each block has a longitudinally extending smooth under surface portion interrupted by a notch or recess 433, Figure 8. When the blocks are in their normal inoperative or "zero" position, the tapered upper end of a locking detent 434 mounted in the housing 359 and biased upwardly by a spring 434b engages the V-notch 433 of inner block 426; and the tapered end of a similar detent 434a biased upwardly by a spring 434c engages the V-notch 433 of outer block 427.

At the lower end of the shank of each upwardly biased detent 434, 434a, is a laterally extending lug 435 which bears yieldingly against the bottom edge of a cam bar 438 slidably mounted in a transverse slot having an opening 439 through the outer side wall of the housing 359, Figure 8. Said bottom edge of cam bar 438 is interrupted by two end recesses having oblique portions forming the cam surfaces 436 and 437, respectively, and by an intermediate recess 436a adjacent to cam surface 436.

An inner end portion of said cam bar 438 is connected by a link 458 with a lever 459 secured at an intermediate portion of a control shaft 460 which is rocked to and from different angular positions by any suitable means, as, in the illustrated embodiment, by the operation of automatic control devices of which parts, including link 808, are shown in Figures 1 and 14.

As seen in Figures 8, 12 and 13, the housing 359 has a top opening 440 through a portion of its top wall above the ratchets 429 and 430. A sliding reciprocatable head 441 carries a pair of plunger pawls 442 and 443, respectively, which are spring biased downwardly and extend through said opening 440. Pawl teeth provided at the lower ends of said pawls and which, in gusset forming operation, cooperate with the ratchets 429 and 430 respectively, are held normally in "up" or disengaged position above said ratchets by the head 444 of a spring pressed plunger 445 when the latter is held in "up" position. A tension spring 445a biases said plunger 445 downwardly, Figures 8 and 12. But the bottom end of said plunger 445 normally bears on a portion of the top edge of cam bar 438 at one side (left) of notch 446 to hold plunger 445 in "up" position. Thus, the head 444 of said plunger, normally engages the downwardly exposed shoulders 447 of said spring biased plunger pawls 442 and 443 and holds said pawls in "up" position and out of engagement with their respective ratchets.

As seen in Figure 12, the head 441 which carries said pawls 442 and 443 is pivotally connected to one end of a link 448 at 449; and periodic reciprocating movement is imparted thereto by means including a lever 450, Figures 2 and 5, secured at an outer end portion of a transverse rock shaft 451, Figure 6. Lever 450 has a curved slot 452, Figure 5, adjacent to which may be placed indicia, as numeral markings, to indicate different effective lengths of said lever which correspond to different numbers of needles to be involved in a given shoulder slant or gusset narrowing operation for any course or courses. Accordingly, the outer end of link 448, is releasably and adjustably secured to said lever 450 by suitable means, as a bolt 453, Figure 5, extending through said slot at one or another of said indicated positions. Suitable adjustment of said connection along slot 452 selectively determines the length of stroke of head 441 and, therefore, of the plunger pawls 442 and 443.

Regular periodic reciprocating movement of head 441 is effected through said lever 450 from the cam shaft 9 which has the bevel gear 12 meshing with bevel gear 15 on transverse shaft 16, Figure 2. As seen in Figures 2 and 7, rock shaft 451 carries a lever 454 near its inner end. A cam roller 455 at the free end of said lever 454, is disposed in the paths of a crescent cam 456 and a lobe cam 457 on the rear surface of said bevel gear 15, Figures 5 and 7. When the free end of lever 454 is rocked to its down position, dotted line Figure 5, head 441 is brought to its extreme left position. Continued turning of gear 15 brings lobe cam 457 into engagement with cam roller 455 thus rocking said free end of lever 454 into "up" position, whereby head 441 is brought to its extreme right position. The extent of this movement of head 441 will, of course, be determined by the relative position of engagement of link 448 along curved slot 452, as previously described.

To release said blocks 426 and 427 from locked engagement with locking detents 434 and 434a and to release said plunger pawls 442 and 443 into engagement with the racks on said blocks to produce shoulder slant narrowing, the cam bar 438, Figure 8, is thrust outwardly, left from the position shown in Figure 8, to that shown in Figure 10. This is done by rocking control shaft 460 counterclockwise a predetermined extent to its first or narrowing operative position. The oblique cam edges 436 and 437 at the under side of cam bar 438 thus come into engagement with said lugs 435 to withdraw the locking detents 434 and 434a from notches 433 in the under surfaces of blocks 426 and 427, Figure 10. At the same time, notch 446 in the upper surface of cam bar 438 comes opposite the bottom end of plunger 445 which slides down into said notch 446. This releases head 444 of said plunger from engagement with shoulders 447 of the plunger pawls 442 and 443 which are now spring pressed downwardly into operative engagement with the ratchets 429 and 430 respectively.

The setting of the parts for narrowing, as above described, is timed to occur between successive strokes of pawl head 441 in opposite directions. On the next succeeding stroke thereof, one of said plunger pawls, as 443, operatively engages the ratchet 430 of the outer block 427 moving it to the right, Figure 1, while pawl 442 rides over ratchet 429 of the inner block 426, whereupon the desired number of needles, as indicated at the

edge of slot 452, Figure 5, are idled at one side of the work in the next knitting course.

The following or return stroke of pawl head 441 to the left produces a similar effect on a like number of needles at the opposite edge of the work in the next knitting course by bringing plunger pawl 442 into actuating engagement with ratchet 429. This moves block 426 to the left, Figure 1, while pawl 443 rides over ratchet 430 of block 427. The mode of operation here described may be repeated in successive courses until the desired number of needles have been idled at opposite ends of alternate courses, at which time a different setting or angular positioning of control shaft 460 is made to restore or return the idled needles to active condition.

Quick return from narrowing in shaping or gusset forming

The rack 432 on the under side of outer block 427 continuously engages a gear 461 on a countershaft 462; and the rack 431 on inner block 426 engages a gear 463 on another countershaft 464. In the narrowing operation above described, each of said racks successively rotates its connected countershaft, one in one direction, the other in the opposite direction, arrows Figure 5, to a cumulative extent corresponding to the total number of needles idled in one or more courses of narrowing at one side of the work.

These racks 432 and 431 and gears 461 and 463, along with other connected devices, are thereafter moved in reverse to rapidly return the blocks 427 and 426 to "zero" position and thus to restore the previously idled needles to active knitting condition by a rapid operation as compared to the widening procedure in fashioning. More specifically, for shaping or gusset forming, in each knitting section, all the cumulatively idled needles at one edge are returned to knitting condition in one course; and all the cumulatively idled needles at the other edge are returned in the next following course. The restoration of needles in any given course is effected at that edge of the work toward which the stitch cams are moved in forming that course.

As seen in Figures 2 and 8, countershaft 462 carries at its inner end a bevel pinion 465 which meshes with a bevel gear segment 466 mounted on a hub 467 loosely supported on the "rapid return" shaft 468. Hub 467 also carries a radially extending pawl arm 469 at the free end of which is pivoted a spring biased pawl having a trip 470 at one end and a laterally extending detent 471 at its other end, Figures 2 and 8. A fixed stop in the form of a bolt 472 is threaded in the machine frame with one end extending adjustably into the path of movement of said trip 470.

As indicated in Figure 2, a bevel pinion 473, a bevel gear segment 474, a hub 475, a pawl arm 476 having a trip 477 and a detent 478, and a bolt or stop 479 like those just described are provided for cooperation with said other countershaft 464.

Between said hubs 467 and 475, a collar 480 is secured to shaft 468. One portion (180°) of its peripheral surface is of spiral contour interrupted to form the shoulder or movable stop 481; and another portion (180°) of its peripheral surface of similarly spiraled contour is interrupted to provide shoulder or movable stop 482, Figure 8, angularly spaced 180° from shoulder 481, both of which face counterclockwise. The detents 471 and 478 extend into the paths of rotation of said shoulders or stops 481 and 482 respectively.

As the bevel gear segments 466 and 474, loosely mounted on said return shaft 468, are rotated alternately, in narrowing successive courses, by the bevel pinions on countershafts 462 and 464, respectively, the pawl arms 469 and 476 secured on said segments are deflected clockwise a corresponding angular extent, Figure 8. Thus, the pawl arm 469 is moved step by step from a normal zero position, clockwise, toward the shoulder or stop 481 which, at this phase, is angularly positioned as shown in said Figure 8. With said clockwise movement of pawl arm 469, detent 471 thereon rocks counterclockwise into position to be engaged by shoulder 481. The detent 478 is carried with rotation of arm 476 in the same angular direction toward shoulder or stop 482. Thus, the aggregate angular displacement of pawl arms 469 and 476, respectively, during such narrowing is a measure of the extent of reverse movement effected on the "rapid return" to restore the idled needles at the opposite edges of the work to active knitting condition.

In effecting said rapid return, shaft 468 is rotated 360° counterclockwise, Figure 8, which actuates collar 480 thereon and thus rotates said shoulders 481 and 482 counterclockwise. Said rotation of shoulders 481 and 482 imparts return movement first to detent 471 and then to detent 478, to actuate and so reverse the endwise movement of blocks 426 and 427 in the same sequence.

Said quick return is thus made in two steps, each of which widens one side or edge of the work during said counterclockwise 360° rotation of return shaft 468. Thus, in the first 180° of rotation of said shaft, shoulder or stop 481, in moving 180° counterclockwise, engages detent 471 and thereby pushes pawl arm 469, bevel gear 466, gear 461 and block 427 back to their initial or zero positions before narrowing. When block 427 reaches zero position, it is again locked by engagement of outer plunger 434 with its V-notch 433.

To bring about the first return step, the cam bar 438 is moved by the control devices to its most extended (left) position, Figure 11, where recess 436a comes opposite the lug 435 on detent 434a which is therefore free to move up to locking position, although detent 434 is still held in down position by cam bar 438. And plunger 445 riding on the top edge of cam bar 438 and out of recess 446 is raised to lift the pawls 442 and 443 out of engagement with the ratchets on blocks 426 and 427 which are thus free to return to their respective initial or zero positions.

On the return of block 427 to zero position by operation of the means described, the top end of detent 434a snaps into the V notch 433 thereof. At this point also, the trip 470, in rotating counterclockwise with shoulder 481 and return shaft 468, encounters the end of fixed stop 472, whereupon detent 471 is rocked upward and out of the path of movement of shoulder 481; and return shaft 468 completes its first 180° rotation. The first widened course is now run by the knitting cams.

In the second and final step of "rapid return," which occurs in advance of the next knitting course, further or continued rotation of return shaft 468 to the extent of 180° in the same direction as before brings shoulder 482 to bear against detent 478, thereby returning pawl arm 476 and connected parts including block 426 to their initial or zero positions before narrowing. When block 426 reaches its zero position, it is again locked against endwise movement by en-

gagement of detent 434 with the notch 433 in said block 426.

To effect said second and final return step, cam bar 438 is moved endwise to the right from the position shown in Figure 11 and thus back to its normal or initial position, Figure 8, by a clockwise turn of control shaft 460. This brings the inner notch on the lower edge of said cam bar 438 opposite the lug 435 on detent 434 which is thus freed to move up to locking position. In this reverse movement of cam bar 438, the lower end of plunger 445 rides across and beyond recess 446; and plunger 445 is brought to its initial "up" position, Figure 8, thereby holding the plunger pawls 442 and 443 disengaged from their ratchets on blocks 426 and 427.

With said clockwise turn of control shaft 460, roller 497, Figure 3, on arm 498 is caused to disengage and free the tapered end of rocking lever 491; but shaft 468 continues rotation. As shaft 468 continues to rotate into its second 180°, the detent 478, Figure 2, is moved counterclockwise by shoulder 482, Figure 8, and is rocked upwardly and out of the path of movement of said shoulder when trip 477 encounters fixed stop 479 at the end of said second 180° of rotation of shaft 468. Shoulders 481 and 482 now occupy their initial relative angular positions, as shown in Figure 8.

Rotation of shaft 468 and of the collar 480 thereon, synchronized with the several endwise movements of cam bar 438, as above described, is controlled from control shaft 460 through a clutch having parts operatively interposed between said shaft 468 and main shaft 6. As shown in Figures 2, 3 and 4, a gear 483 is loose on said main shaft 6 adjacent to the hub 484 of gear 7 secured to said main shaft 6 and having a laterally exposed notch 485. Gear 483 has a hub 486 provided with an annular groove 487. A spring biased plunger 488, Figure 4, is slidably mounted in a transverse recess 489 which, at one end, opens through the web of said gear 483 and at its other end intersects a portion of said annular groove 487. One end of said plunger, when extending into notch 485, provides a latch by which said gear 483 is releasably held in driven engagement with the hub of gear 7. Rotation is thereby imparted to gear 490 secured on shaft 468 and controlled to effect a single complete rotation of return shaft 468 for two complete rotations of gear 483.

As seen more clearly in Figures 3 and 4, the position of clutch plunger 488 which is biased by spring 489a toward engagement with notch 485, is controlled by the spring biased rocking lever 491 pivoted at 492. The left end, Figure 3, of said lever 491 is bevelled at 493 to engage a shoulder 494 of the plunger 488, when said left end of lever 491 is held by spring 495 in the de-clutching, or down position shown in Figures 3 and 4.

The right end of lever 491 is tapered to present an oblique upper surface 496 in the path of cam roller 497 on lever 498 (dotted, Figure 8) which is secured at the inner end of shaft 460, Figure 2. Rocking lever 491 also has a vertically extending arm 499, an end portion of which is normally disposed in the path of rotation of a portion of cam 500 projecting from the hub 501 of gear 490, Figure 3.

At times when rapid return widening is not in effect, the bevelled end 493 of lever 491 lies in the annular groove 487 and holds plunger 488 in retracted non-clutching position, Figure 2.

To effect the shoulder slant narrowing pre-

viously described, control shaft 460 is rotated or rocked an initial extent which also rocks end lever 498 thereon counterclockwise, Figure 3, sufficiently to bring roller 497 into a position over the tapered end 496 of lever 491 but not far enough however, to press said end of lever 491 downwardly.

To effect return of the needles idled at one side of the work by the narrowing operations previously described, control shaft 460 and therefore lever 498 are first rocked or rotated counterclockwise to a greater extent than for said shoulder slant narrowing. This greater rotation of shaft 460 carries roller 497 on lever 498 downwardly against the tapered end 496 and so rocks lever 491 against tension of spring 495 to disengage its other or bevelled end 493 from plunger 488 which then snaps into clutching engagement with notch 485 and so initiates the first 180° rotation of return shaft 468 during which the first return step is effected.

To effect return of the remaining needles idled at the other side of the work, control shaft 460 is rotated or rocked clockwise back to its initial or normal position, Figures 3 and 8, and rotation of return shaft 468 continues as hereinafter described until it has completed 360°.

Rotative or rocking movements of control shaft 460 to and from said different operative positions 30 are effected by any suitable means, here shown as automatic control devices including the control link 808, Figures 1 and 14, connected to shaft 460 by an arm 809 cooperating with other instrumentalities.

The first 180° rotation of the return shaft 468 as above described, effects return, through gear 461 and block 427, of the needles previously idled at one side of the work. At this point, those portions of the clutch devices connected with gear 40 7, including loose gear 483 and clutch plunger 488, have turned 360°. Said plunger 488 would be disengaged from notch 485 by the bevelled end 493 of lever 491, if the latter were here returned by spring 495 to the normal angular position shown in Figure 3—which, unless prevented, would occur upon the above described clockwise rotation of control shaft 460. However, to insure the further continued 180° rotation of return shaft 468 for the final widening step, the crest 50 of cam 500 which has turned 180° with return shaft 468, is now in position to bear against and hold vertical arm 499 and therefore lever 491 in tilted position, as when lever 491 is initially rocked clockwise by roller 497 on arm 498. This 55 holds rocker lever 491 disengaged from annular groove 487 until continued rotation of gear 483 carries the plunger 488 past its clutch disengaging position.

As appears from the foregoing description and stated mode of operation, apparatus according to my invention affords an effective and relatively simple means for conditioning the needles in a knitting machine so as to produce products having fullness. When applied to a full automatic machine, wherein provision is made for fashioning, said gusset forming or shaping devices utilize portions of the fashioning devices, thus attaining the additional production features with a minimum of special or additional parts.

A further advantage of my improved device, as described, is that it operates effectively with automatic control at high knitting speeds, i. e. of the order of 45-55 courses per minute on a multiple unit machine.

The above described mechanisms are also shown

and described but not independently claimed in my co-pending application Serial No. 530,761, filed herewith and of which the present application is in effect a division.

I claim:

1. In a straight independent needle knitting machine having devices adjustable in one direction to idle the needles and in the opposite direction to return needles to active condition, the combination of a shaft mounted to rotate in opposite directions and for reciprocating endwise movement, means operatively connecting said shaft with said devices including a nut threaded thereon, means for rotating said shaft in opposite directions to effect movement of said nut thereon, and means for imparting endwise movement to said shaft to effect movement of said nut therewith.

2. In a straight independent needle knitting machine having devices adjustable in one direction to idle the needles and in the opposite direction to return needles to active condition, the combination of a shaft mounted to rotate in opposite directions and for reciprocating endwise movement, means operatively connecting said shaft with said devices including a nut threaded thereon, means for rotating said shaft in opposite directions to effect movement of said nut thereon, means for imparting step by step endwise movement to said shaft in one direction to effect corresponding movement of said nut, and means for imparting endwise movement in the opposite direction to effect corresponding movement of said nut.

3. In shaping or gusset forming mechanism for straight knitting machines having independent needle jacks and needles and devices for idling and for restoring them to active condition, the combination of an actuating member mounted for adjusting movement, means for moving said member step by step in one direction, other means for moving said member in the opposite direction, and needle jack conditioning means actuated by adjusting movements of said member and operatively connected to said actuating member and to said idling and said activating devices, whereby said needle jacks are conditioned for idling by said step by step movement of said member in one direction and are restored to active condition by said movement of said member in the opposite direction.

4. In shaping or gusset forming mechanism for straight independent needle knitting machines in which means are provided for narrowing and widening by adjusting needle positioning push jacks one after another into and out of idle position, the combination of a cam carrier mounted for endwise adjusting movement, a widening cam and a narrowing cam mounted on said carrier, means operatively interposed between said cams and said jacks to transmit adjusting movement from said cams to said jacks, means for moving said carrier step by step in one direction to adjust said jacks to idle condition, and means for moving said carrier in the opposite direction to adjust said jacks to active condition.

5. In shaping or gusset forming mechanism for straight independent needle knitting machines in which means are provided for narrowing and widening by adjusting needle positioning push jacks one after another into and out of idle position, the combination of a pair of cam carriers mounted for endwise adjusting movement, a widening cam and a narrowing cam mounted on each of said carriers, means operatively inter-

posed between said cams and said jacks to transmit adjusting movement from said cams to said jacks, means for moving said carriers step by step in opposite directions to adjust said narrowing cams one toward the other, and means for moving said carriers in the opposite direction to adjust said widening cams one away from the other.

6. In shaping or gusset forming mechanism for straight independent needle knitting machines in which means are provided for narrowing and widening by adjusting needle positioning push jacks one after another into and out of idle position, the combination of a pair of cam carriers mounted for endwise adjusting movement, a widening cam and a narrowing cam mounted on each of said carriers, means operatively interposed between said cams and said jacks to transmit adjusting movement from said cams to said jacks, means for moving said respective carriers step by step in successive courses to adjust said narrowing cams one toward the other, and means for moving said respective carriers in successive courses to adjust said widening cams one away from the other.

7. In shaping or gusset forming mechanism for straight independent needle knitting machines wherein a widening cam and a narrowing cam are mounted on a cam carrier which moves in one direction to actuate the widening cam and in the opposite direction to actuate the narrowing cam, the combination of a ratchet operatively connected to said cam carrier and movable therewith, a rack operatively connected to said cam carrier and movable therewith, a pawl biased to engage said ratchet, means for reciprocating said pawl and thereby to move said cam carrier and said rack step by step in one direction for narrowing, means for disengaging said pawl from said ratchet, and means for moving said rack in the opposite direction to actuate said widening cam.

8. In shaping or gusset forming mechanism for straight independent needle knitting machines wherein a widening cam and a narrowing cam are mounted on a cam carrier which moves in one direction to actuate the widening cam and in the opposite direction to actuate the narrowing cam, the combination of a ratchet operatively connected to said cam carrier and movable therewith, a rack operatively connected to said cam carrier and movable therewith, a pawl biased to engage said ratchet, means for reciprocating said pawl and thereby to move said cam carrier and said rack step by step in one direction for narrowing, means for disengaging said pawl from said ratchet, a rotatable stop having a normally fixed angular position, an arm mounted concentrically with said rotatable stop and having a detent portion movable with said arm in the path of rotation of said stop, means operatively interposed between said rack and said arm to transmit movement to and from said detent and said rack, and means for rotating said stop from said normal position toward and into moving engagement with said detent to effect widening movement of said rack.

9. In shaping or gusset forming mechanism for straight independent needle knitting machines wherein a widening cam and a narrowing cam are mounted on a cam carrier which moves in one direction to actuate the widening cam and in the opposite direction to actuate the narrowing cam, the combination of a ratchet operatively connected to said cam carrier and movable there-

with, a rack operatively connected to said cam carrier and movable therewith, a pawl biased to engage said ratchet, means for reciprocating said pawl and thereby to move said cam carrier and said rack step by step in one direction for narrowing, means for disengaging said pawl from said ratchet, a rotatable stop having a normally fixed angular position, an arm mounted concentrically with said rotatable stop, a detent pivotally mounted on said arm and having one end portion biased into the path of rotation of said stop, means operatively interposed between said rack and said arm to transmit movement to and from said detent and said rack, a trip arranged at one end of the path of movement of said detent, and means for rotating said stop from said normal position toward and into engagement with said detent to move another end portion of said detent into operative tripping engagement with said trip.

10. In shaping or gusset forming mechanism for straight independent needle knitting machines wherein a widening cam and a narrowing cam are mounted on a cam carrier which moves in one direction to actuate the widening cam and in the opposite direction to actuate the narrowing cam, the combination of a ratchet operatively connected to said cam carrier and movable therewith, a rack operatively connected to said cam carrier and movable therewith, a pawl biased to engage said ratchet, means for reciprocating said pawl and thereby to move said cam carrier and said rack step by step in one direction for narrowing, means for disengaging said pawl from said ratchet, a rotatable stop having a normally fixed angular position, an arm mounted concentrically with said rotatable stop, a detent pivotally mounted on said arm and having one end portion biased into the path of rotation of said stop, means operatively interposed between said rack and said arm to transmit movement to and from said detent and said rack, a trip arranged at one end of the path of movement of said detent, and means for rotating said stop from said normal position toward and into engagement with said detent to move another end portion of said detent into operative tripping engagement with said trip, a continuously rotating drive shaft, a clutch operatively interposed between said drive shaft and said means for rotating said stop, means for actuating said clutch to effect operative connection between said drive shaft and said rotatable stop, and means operatively connected with said rotatable stop and with said clutch actuating means to disengage said clutch simultaneously with the tripping of said detent.

11. In shaping or gusset forming mechanism for straight independent needle knitting machines wherein a widening cam and a narrowing cam are mounted on each of a pair of cam carriers one of which moves in one direction in one course and the other of which moves in the opposite direction in the next course to actuate said cams,

the combination of means for effecting step by step movement of said carriers in opposite directions in successive courses, a pair of rotatable stops angularly spaced 180° apart, a pair of rotatable arms each of which is operatively connected with one of said cam carriers and each of which has a detent portion movable therewith in the path of rotation of one of said stops, means for transmitting movement between each of said carriers and one of said arms, and means for rotating said stops in one direction to bring one thereof into engagement with one of said detents and then the other thereof into engagement with the other of said detents to effect widening movements of said carriers in two successive courses.

12. In shaping or gusset forming mechanism for straight knitting machines having independent needle jacks and needles and conditioning devices for idling and for restoring them to active condition, the combination of a cam actuating member mounted for adjusting movement, means for moving said member step by step in one direction, means other than said last mentioned means for moving said member in the opposite direction, and cam means actuated by adjusting movements of said member and operatively connected to said conditioning devices whereby said needle jacks are conditioned for idling by said step by step movement of said member in one direction and are restored to active condition by said movement of said member in the opposite direction.

13. In shaping or gusset forming mechanism for straight knitting machines having independent needle jacks and needles and needle jack conditioning devices movable in one direction for narrowing and in the opposite direction for widening, the combination of cam means arranged and adapted to engage and actuate a portion of said needle jack conditioning devices, means for moving said cam means step by step in one direction to actuate said jack conditioning devices for narrowing and means other than said last mentioned means and arranged and adapted to move said cam means in the opposite direction to actuate said jack conditioning devices for widening.

14. In shaping or gusset forming mechanism for straight knitting machines having independent needle jacks and needles, and needle jack conditioning devices movable in one direction for narrowing and in the opposite direction for widening, the combination of cam means arranged and adapted to engage and actuate a portion of said needle jack conditioning devices, means including a pawl and a ratchet for moving said cam means step by step in one direction to actuate said jack conditioning devices for narrowing and means including a rack and a pinion arranged and adapted to move said cam means in the opposite direction to actuate said jack conditioning devices for widening.

THOMAS S. HAYHURST.
